United States Patent Office.

GEORGE E. BURT AND EDWIN A. HILDRETH, OF HARVARD, MASSACHUSETTS.

Letters Patent No. 90,991, dated June 8, 1869.

IMPROVEMENT IN FORKS FOR HAY-SPREADERS.

The Schedule referred to in these Letters Patent and making part of the same.

To all whom it may concern:

Be it known that we, GEORGE E. BURT and EDWIN A. HILDRETH, both of the town of Harvard, county of Worcester, and State of Massachusetts, have invented a new and useful Improvement in Hay-Tedder Forks; and we do hereby declare that the following is a full and exact description thereof, reference being had to the accompanying drawings, and to the letters of reference marked thereon, in which—

Figure 1 is a front or top view of the fork complete.

Figure 2 is a side view of the same fork.

Figure 3 is a front view of the left-hand tine, B, of the fork, with its coil and shank.

Figure 4 is a front view of the right-hand tine, A, of the fork, with its coil and shank.

Figure 5 is a view of the bolt *k*, which connects the two parts of the fork.

Figure 6 is a view of the nut *L*, showing the boss *n*.

Figure 7 is a horizontal longitudinal section of the bolt *k*, showing the seat *o* for the shank *D* of the tine *B*.

Figure 8 is a vertical section through the middle of the nut *L*, showing the seat *o'* in the boss *n* for the shank *C* of the tine *A*.

Like letters represent like parts in all the figures.

It has been found, by experience, that hay-tedder forks should be constructed of the best elastic spring-tempered wire, in order to have them keep their form, and yield to obstacles with which they may come in contact when in operation.

It has been found, that in constructing forks with both tines made of the same piece of wire, it is necessary to bend the wire at very short angles, in order to construct the loop that connects the two tines. In constructing these loops, the wire is severely strained, and is liable to break in making, or to fail after being put in use; and it is found necessary to use a softer or lower-tempered wire to construct forks in this manner; and, when wire is used that will bend sufficiently to make the angles of the forks so constructed, such forks are not sufficiently elastic to pass obstacles without being greatly injured.

To overcome the above objections is one of the objects of this invention; and

The nature of our invention consists in constructing hay-tedder forks in separate parts, in such a manner that each of the parts may be easily removed or repaired, and yet there is no liability of said parts being loosened by the action of the machine when in operation; also, to enable the manufacturer to use a higher-tempered and very elastic grade of wire in constructing the forks to hay-tedders, having all the advantages of a fork constructed of one piece of wire, and also of having more perfect pivots and shoulders for the connecting arms that operate the forks.

To enable others skilled in the art to make and use

our invention, we will proceed to describe its construction and operation.

We construct our forks of two parts, A and B, provided with shanks C and D, tines G and H, and coils I and I', of sufficient diameter to receive the support J, figs. 1 and 2.

On the end of the shanks C and D, we cut screw-threads, figs. 3 and 4.

We construct screw-bolt *k*, with either round or square head, *m*, and with screw-thread on its end, which is made to fit a screw-thread in the nut *L*, fig. 5.

Nut *L* is constructed with the boss *n*.

The bolt-head *m* and boss *n* are provided with seats *o* and *o'*, figs. 7 and 8, having screw-threads cut in them, to fit the screw-thread on the shanks C and D, figs. 3 and 4.

The shank D is screwed into the seat *o* in the bolt-head *m*, and the shank C is screwed into the seat *o'* of the boss *n*. The part A is then screwed, by the screw-nut *L*, on to the bolt *k*, which forms a very strong and firm connection between the two parts A and B, fig. 1.

The support J is passed into the coils I and I', which are held laterally in position by stop P, which is fixed to support J by screws, seen in fig. 1.

R is the connecting-arm which operates the fork.

Operation.

It will be seen, that when a fork of this construction is placed, on its supporting-bar J, in a tedder of common construction, all its parts are held securely in position by the bar J, which sustains the coils I and I' of the parts A and B.

As the nut *L* cannot turn on the bolt *k*, nor the shanks C and D turn in their seats in the boss *n* or bolt-head *m*, all the parts of the fork are securely held in place, with no liability of unscrewing when in operation, and the operating-force may be applied to the fork at any angle, or in any position, with the same effect as in a fork made of a single piece of wire.

The body of the bolt *k*, being straight, forms a superior pivot for the connecting-arm R, that operates the tedder-fork.

The shoulders formed by the bolt-head *m* and nut *L* are important features peculiar to this fork. They hold firmly, and guide in a right direction the connecting or operating-arm R of the tedder, and cause the fork to play with less friction when in operation.

Thus, a very superior fork may be constructed, as firm, and more reliable than it would be if made entire, of one piece of wire, as usually employed, and of wire of high grade of temper, and of such elasticity that the forks will not be bent out of place by coming in contact with obstacles when in operation.

The entire fork, or either of the parts, may be re-

moved by taking out the support *J*, and unscrewing either part. Thus any of the parts may be readily removed for repairs or transportation.

What we claim, and desire to secure by Letters Patent, is—

1. In combination with a hay-tedder, a spring-fork constructed of two separate pieces of wire, when arranged to rock on the support *J*, and connected firmly together by the bolt or pivot *k*, in such a manner as to hold the pivot *k* in its proper position without any other connection than the shanks of the fork, between the pivot or bolt *k*, and the bearing upon which the coils of the fork are supported, substantially as described.

2. The bolt *k* and nut *L*, when provided with seats

for the shanks *C* and *D*, in combination with a hay-tedder fork, substantially as described.

3. The nut *L*, when constructed with a boss, *n*, provided with a seat, *o*, substantially as described, in combination with a hay-tedder fork.

4. The combination of the operating-arm *R*, turning upon the bolt *k*, the tedder-forks *A* and *B*, constructed of separate pieces of wire, and the bolt *k*, with shoulders on each side of the operating-arm, to keep it in position, substantially as described.
